UNITED STATES PATENT OFFICE

165,519

TRAY

George A. Francis, Baldwin Park, Calif.

Application August 4, 1951, Serial No. 16,155

Term of patent 7 years

(Cl. D44—10)

To all whom it may concern:

Be it known that I, George A. Francis, a citizen of the United States of America, residing at Baldwin Park, county of Los Angeles, State of California, have invented a new, original, and ornamental Design for a Tray, of which the following is a specification, reference being had to the accompanying drawing, forming a part hereof.

Referring to the drawing:

Fig. 1 is a plan view of my tray, and Fig. 2 is a side elevation thereof.

Fig. 3 is a bottom view of my tray.

I claim:

The ornamental design for a tray, substantially as shown.

GEORGE A. FRANCIS.
